J. H. DORAN,
EXTRACTION AND MIXED PRESSURE TURBINE,
APPLICATION FILED JUNE 14, 1918.

Patented Aug. 17, 1920.

Inventor:
John H. Doran,
by *John H. Doran*,
His Attorney.

UNITED STATES PATENT OFFICE.

JOHN H. DORAN, OF SCHENECTADY, NEW YORK, ASSIGNOR TO GENERAL ELECTRIC COMPANY, A CORPORATION OF NEW YORK.

EXTRACTION AND MIXED-PRESSURE TURBINE.

1,349,878.

Specification of Letters Patent. Patented Aug. 17, 1920.

Application filed June 14, 1918. Serial No. 239,942.

To all whom it may concern:

Be it known that I, JOHN H. DORAN, a citizen of the United States, residing at Schenectady, in the county of Schenectady, State of New York, have invented certain new and useful Improvements in Extraction and Mixed-Pressure Turbines, of which the following is a specification.

The present invention relates generally to elastic fluid turbines of the type having a radial flow blade system comprising two blades carrying elements or rotors arranged to rotate in opposite directions, each element delivering power to a shaft which, for example, may be connected to the rotor of an electric generator or other power consuming agent.

The object of my invention is to provide an improved arrangement of parts whereby steam at an intermediate pressure can be extracted from the blade system after it has performed work in the turbine or whereby intermediate or low pressure steam can be admitted to the turbine to perform work therein in the low pressure stages or portion.

For a consideration of what I believe to be novel and my invention, attention is directed to the accompanying description and claims appended thereto.

In the drawing, Figure 1 is a partial sectional view of a turbine having oppositely rotating blade systems; Fig. 2 is a detail view of a part of the steam chest taken on line 2-2 of Fig. 1; Fig. 3 is a detail view of a portion of the auxiliary steam chest, and Fig. 4 is a sectional view of the steam chests.

5 indicates the inner portion of one of the 40 rotors which is mounted on a stub shaft 6, the latter in turn being connected to one of the main shafts (not shown). To the said inner portion is connected an intermediate rotor portion 7, by an expansion ring 45 8. 9 indicates the outer rotor portion which is connected to the intermediate portion by the expansion ring 10. The right hand side of the machine is a duplicate of the left and for that reason can be readily understood 50 without further illustration.

To the inner, intermediate and outer portions of the rotor are connected concentric rings or blades 11, each of which is secured

to the rotor by an expansion ring 12 which is similar to but of smaller size than the expansion rings which connect the parts of the rotor. As will be seen these expansion rings are provided with enlarged rounded extremities 13, which are seated in sockets formed in the rotor itself or in anchoring rings carried thereby. The purpose of these expansion rings is to divide the parts into regions or zones of different temperatures, the transfer of heat through said rings being relatively slow and restricted. Furthermore, these rings permit the parts to expand and contract at different rates without causing the stresses in one part being transmitted to the other parts. They also serve as means to prevent the escape of steam between different parts as will be evident upon inspection.

Located between the blade rings 11 are other and concentric blade rings 14 which are supported in the same manner by the right hand rotor portions. The outer portion 9 of the rotor is also provided with radially extending blades or buckets 15 through which low pressure steam flows in an axial direction. 16 indicates stationary nozzles or fluid discharging devices which receive steam from the radial flow blade system of the machine, *i. e.*, the rings of blades 11 and 14, and deliver it to the axial flow portion, only one of which is illustrated. The nozzles are supported by rings 17 and 18 which in turn are supported by an annular member 19 and diagonal braces 20. The member is supported by an annular rib 21 on the inside of the inclosing casing 22 and also by one or more pins 23 which hold it against turning.

Since the rotors in such a turbine are subjected to axial thrusts due to the passage of steam between them a thrust absorbing and balancing means has to be provided on each side of the machine. In the present case each means comprises a pair of disks 24 and 25, of which the disk 24 rotates while the disk 25 is stationary. To reduce the leakage between the disks the opposed faces thereof are provided with a labyrinth packing 26 of any suitable construction, in this case alternate projections and grooves. Through this packing live steam flows radially from the center toward the outside and

as the pressure therein from point to point substantially corresponds to that of the steam flowing radially at corresponding points through the blades the axial position 5 of the rotor will be maintained.

27 indicates a steam chest having an inner annular chamber 28 to which live steam is admitted by the supply pipes 29, and an outer annular chamber 30 to which live 10 steam is also admitted for heavy or overload conditions by an overload valve 30^a shown in dotted lines. The chest is supported by a plate 31 which is secured to the inside of the casing of the turbine in 15 any suitable manner. Between the plate and chest is an expansion ring 32 acting as the other expansion rings do to compensate for unequal stresses due to temperature changes. The thrust and balancing disk 20 25 is carried by the stationary steam chest, said parts being united by two concentrically arranged expansion rings 33 which rings in addition to forming a supporting means also form steam tight joints to prevent 25 leakage of steam from the chest. Steam from the main supply chamber 28 flows to the inner blades near the axis of the machine in the manner indicated by the arrows 34. Steam from the overload chamber 30 flows through a series of uniformly spaced axially extending holes or passages 35, 36, and 37 in the thrust and balancing disks and inner portion 5 of the rotor to an intermediate pressure region of the blade 35 system.

Referring now to the arrangement of parts whereby steam may be extracted from the turbine for heating purposes, or whereby low pressure steam may be admitted to perform work in the turbine, 40 indicates an auxiliary steam chest which may be supported in any suitable manner, preferably by the main chest. It may be made integral therewith or it may be bolted 45 thereto, as shown in the drawing. The arrangement will be determined principally by the construction of the main steam chest. If the latter is a forging the auxiliary chest will be made separate; if a casting, the two 50 chests may be made in one piece. Mounted or formed on the main chest is a shoulder 41 to which the auxiliary chest is secured by bolts 42, and in said shoulder are holes or passages 43 registering with similar 55 holes or passages in the auxiliary chest and through which steam may enter or leave the turbine. To the shoulder 41 is attached by an expansion ring 44 an annulus 45 forming part of an axial packing. Surrounding this annulus and forming the 60 other part of the packing is a second annulus 46 which is secured to the intermediate part of the rotor, by an expansion ring 47. The opposed faces of the two 65 parts are provided with alternate grooves

and projections or other means to reduce the leakage of steam, it being noted that the pressure at the left hand end of the packing corresponds to that of the exhaust while the opposite end is considerably higher and 70 corresponding to the pressure at the periphery of the thrust and balancing disks. Between the right hand end of the annulus 45 and the disk 25 is a narrow conical passage or space 48 through which steam for 75 extraction purposes passes from the rotor and from the space between the thrust and balancing disks 24 and 25. Steam from an intermediate pressure region in the rotor flows laterally through the axial holes or 80 passages 49 in the intermediate portion 7 of the rotor as indicated by the small arrows. The passages 49 which open laterally from the main steam path should be numerous so as to equalize the flow of steam from 85 the region of intermediate pressure between the parts of the blade system. The passages are shown extending axially since this is the simplest construction but they may be formed otherwise if desired. If low pressure steam is supplied from an external source the flow of steam is of course in the 90 opposite direction but through the same passages.

In order to convey steam from or to the 95 turbine the auxiliary steam chest is provided with an extension on its upper side in which is seated the pipe 50, the latter extending through the wall of the turbine casing in any appropriate manner. As 100 shown, two auxiliary steam chests are provided for each side of the machine, there being in all four pipes 50, of which two are shown.

When operating as an extraction machine 105 under normal load conditions, steam will issue from the numerous passages 49 at about 15 lbs. gage pressure, for example, into the annular equalizing chamber 51 from which it flows over the periphery of 110 the thrust and balancing disks into the annular chamber 52 and thence through the passages 43 into the auxiliary chests 40 and outlet pipes 50. The pressure of the steam leaving the packing space between the disks 115 would under the conditions described also be about 15 lbs. gage, and steam from both sources would flow into the chamber 52. At loads other than normal, the pressure at the periphery of the disks would vary in approximately the same ratio as that of the steam issuing from the passages 49 in the intermediate part of the rotor 7.

When operating as a mixed pressure machine the steam issuing from between the 125 disks would flow with the steam from the outside source into chamber 51 and thence through the numerous passages 49 into the blade system.

It will be seen that by taking steam from 130

or admitting it to both sides of the rotor in the same region, the axial balance of the rotor is not disturbed, a feature of the utmost importance in a turbine of this type 5 where the parts of the blade system revolve in opposite directions and where the clearances are small.

As previously stated there are two packings, one a radial flow packing and the 10 other an axial flow packing. This arrangement is made necessary by the fact that sufficient balancing pressure cannot be had if the steam is allowed to expand to the exhaust pressure of the turbine at the outside 15 diameter of the balancing disks. Sufficient balancing pressure could be obtained if the diameter of the radial packing could be made greater but this is impossible because the bore of the surrounding wheel cannot 20 be enlarged on account of the high stresses in its hub. The provision of the axial flow packing, however, in series with the radial flow packing permits of the necessary increase of pressure at the outside diameter 25 of the balancing disks and radial packing. I take advantage of the fact that two packings are required by providing a steam passage between them, and by utilizing this passage along with passages 49 in the rotor 30 and also chambers 51 and 52 and auxiliary steam chests 40 it is apparent that steam can be extracted from or admitted to the turbine without essentially modifying the structure of the turbine itself.

35 In the broader aspects of my invention it is not limited to having oppositely rotating blades since one set of blades can rotate while the others are held stationary. However, the double rotation system is preferable 40 because of its superior efficiency. Neither is it limited in its broader aspects to having an axial flow packing in series with the radial flow packing for in some instances it is possible to provide two radial flow packings and obtain the desired result, 45 in all cases, however, steam admitted to or flowing from the auxiliary chest will flow through the space between the two packings.

In accordance with the provisions of the 50 patent statutes, I have described the principle of operation of my invention, together with the apparatus which I now consider to represent the best embodiment thereof; but I desire to have it understood that the apparatus shown is only illustrative and that the 55 invention can be carried out by other means.

What I claim as new and desire to secure by Letters Patent of the United States, is:—

60 1. In an elastic fluid turbine, the combination of relatively rotating parts, two separate sets of packings for reducing leakage, said sets of packings being spaced to form an annular passage between them, fluid conveying means which connects a region of intermediate pressure in said rotating parts

with the passage between said packings, and means communicating with the outside of the turbine and through which fluid can flow into or from said passage.

2. In an elastic fluid turbine, the combination of relatively rotating parts, sets of packings for reducing leakage between the rotating part and the turbine casing, fluid passages in one of said parts, a chamber adapted to receive fluid from or admit it to 70 said passages, a chest having a chamber in communication with the first mentioned chamber, and a conduit opening into the chest and also to the outside of the casing.

3. In an elastic fluid turbine, the combination of rotors having blades which rotate in opposite directions, said rotors having passages opening into a region of intermediate pressure, sets of packings on opposite sides of the rotating structure, the packings 80 on each side being separated by a steam passage which is in communication with certain of the first named passages, steam chests on opposite sides of said rotors which communicate with said steam passages, and 90 conduits for conveying steam between the chests and the outside of the turbine casing.

4. In an elastic fluid turbine, the combination of a rotor having a radial flow blade system and also passages which open into a 95 region of intermediate pressure in the blade system, a pair of thrust and balancing disks, a labyrinth packing between the disks, a second packing through which exhaust from the labyrinth packing flows, the two packings being separated by a passage through which steam flows to or from said passages in the rotor, a steam chest which communicates with the passages, and a conduit for conveying steam to or from the chest.

5. In an elastic fluid turbine, the combination of a rotor which has a radial flow blade system, a pair of thrust and balancing disks, one of which is connected to the rotor, a labyrinth packing between the disks, passages in the rotor through which steam may flow into or from the rotor and over the periphery of the disks, a second packing which maintains a pressure at the end of the labyrinth packing above the turbine exhaust 115 pressure, a main steam chest supported by the casing which carries one of the thrust disks, an auxiliary chest which communicates with the region between the two packings, and a conduit through which steam 120 flows into or from the auxiliary chest.

6. In an elastic fluid turbine, the combination of a rotor having a radial flow blade system, a pair of thrust and balancing disks, a packing between the disks to reduce leakage, a second packing receiving the steam from the first and comprising two annular bodies, one of which is carried by the rotor, a steam chest which is supported by the turbine casing and in turn carries the second 125 130

annular body of the packing, and a conduit communicating with the chamber in the chest.

7. In an elastic fluid turbine, the combination of a rotor having a radial flow blade system and also lateral passages, a pair of thrust and balancing disks, one of which is connected to the rotor, a packing between the disks to reduce leakage, a steam chest which is supported by the turbine casing, supplies steam to the blade system and also supports one of the disks, a second packing which receives steam from the first and comprises two concentric annular bodies, one of which is supported by the rotor, and the other by the steam chest, an auxiliary chest which is in communication with the lateral passages in the rotor and the space between the packings; and a conduit opening into the auxiliary chest.

8. In an elastic fluid turbine, the combination of a rotor having radial and axial flow blade systems, a pair of thrust and balancing disks, one of which is carried by the rotor, a packing between the disks, a stationary annular steam chest located between a wall of the turbine casing and the rotor which supports one of the disks, a second packing which receives exhaust from the first and comprises two concentric annular bodies, said bodies being located within that portion of the rotor which carries an axial flow blade system, means for attaching one of the bodies to that portion of the rotor which carries a radial flow blade system, and means for at-

taching the other body to the stationary steam chest.

9. In an elastic fluid turbine, the combination of rotors having oppositely rotating blades, a pair of thrust and balancing disks for each set of blades, one of which is carried by a rotor, a stationary steam chest which supports the second disks, an axial packing which surrounds the disks, one part of which is attached to the rotor and the other to the steam chest, the latter part coöperating with the steam chest to define a chamber which is in communication with the region between the periphery of the disks and the packing, an auxiliary steam chest which is in communication with the chamber, and a conduit connected to the chest.

10. In an elastic fluid turbine, the combination of bladed rotors which revolve in opposite directions, said rotors having sets of laterals passages, one set supplying steam for overload purposes, the second set being arranged to discharge steam for extraction purposes and to receive steam for mixed pressure operation, thrust and balancing disks, leakage reducing packing means between the edges of the disks and the final exhaust, means for admitting steam to the first set of lateral passages, and means for conveying steam over the edges of the disks to or from the second set of lateral passages.

In witness whereof, I have hereunto set my hand this 12th day of June, 1918.

JOHN H. DORAN.
